PUSH-BUTTON SWITCH

Clarence D. Gross, Cuyahoga Falls, Ohio

Application March 3, 1949, Serial No. 79,390

1 Claim. (Cl. 200—159)

1

This invention relates to a push-button switch device.

One object of the present invention is to provide an improved push-button switch device which utilizes a casing of resilient material and an inherent tendency of the casing to resume normal given shape, to obviate separate movable parts usually provided in push-button switches, and at the same time reducing the switch to extremely simple form and consequently reducing the cost of manufacture to a minimum.

Another object of the invention is to provide a push-button switch of the character described which may be installed on a wall, for example, by the simple expedient of fastening the unit in place, as by means of several screws, in cooperation with two spaced contact projections provided on said wall.

Other objects of the invention will be manifest by the following brief description and the accompanying drawings.

Of the accompanying drawings:

Figure 1 is a front elevation of the casing of a push-button switch embodying the features of the invention.

Figure 2 is a vertical cross-section taken substantially on the line 2—2 of Figure 1.

Figure 3 is an enlarged fragmentary view of the central portion of the switch casing shown in Figure 2, and illustrating the manner of applying a contact disc.

Figure 4 is a cross-section, corresponding to Figure 2, but illustrating a complete switch device, installed on a wall in cooperation with a pair of contact points in a bell circuit.

Figure 5 is a view similar to Figure 3, illustrating a modified form of the invention.

Referring particularly to Figures 1, 2 and 3, the numeral 10 designates a vulcanized, semi-hard rubber casing, for a push-button switch, the same being formed hollow and dome-shaped from the inner edge of an integral annular flange 11, which has circumferentially spaced apertures 11a therein for reception of fastening screws (see Figure 4).

At the central inner portion of the dome part 12 is an integral inward projection 13, which extends to a point spaced from the plane of said annular flange. Received on the inner end portion of projection 13, against the resiliency of the rubber thereof, is an apertured disc 14 of electro-conductive material the aperture 15 of the disc being slightly smaller in diameter than the projection. The manner of yieldingly forcing the

disc onto the projection is illustrated in full and chain-dotted lines in Figure 3.

A button 16, also integral with the casing, is provided at the central outer portion of dome part 12, in alignment with central projection 13, for operating the device in a manner to be described.

In use of the improved push-button device of Figure 3, it is mounted on a wall as by means of a plurality of screws 17, 17 received through the apertures 11a in flange 11, to have the disc 14 overlying the projecting heads of two screws 18 and 19 in said wall and forming contacts in an electric bell or other circuit desired to be closed at will (see Figure 4). The contacts 18 and 19 are arranged so that by manually depressing the button 16, against the inherent resiliency of the dome part 12, engagement of the disc 14 with both said contacts will close said electric circuit. As soon as the button is released the casing 10 will resume normal vulcanized shape and thereby break the contact between disc 14 and contacts 18 and 19.

Figure 5 shows a modified form of the invention which is like that shown in Figure 3, except that an annular groove 13a is provided adjacent the end of the inner projection 13, for reception of the inner edge portions of a ring 14a similar to ring 14, thereby providing means for accurately locating the ring on the projection wall as for retaining it in place.

Thus has been provided an improved push-button switch which may be sold an as extremely simple unit comprising only two primarily essential parts, namely the dielectric casing and the electro-conductive disc attached thereto. The unit is easy to install for use, as described, and there are no springs or other parts to wear and get out of order. The dome-shaped casing may be utilized with other types of electrical contact means than described above.

Other modifications of the invention may be resorted to without departing from the spirit thereof or the scope of the appended claim.

45 What is claimed is:

A self-supporting one-piece push button switch for use in an electric circuit including contact means, comprising, a hollow dome-shaped casing of dielectric resilient material in the nature of vulcanized rubber, said hollow dome-shaped casing defining an annular edge portion, substantially in the plane of attachment a push button integral with said casing and projecting outwardly of the central portion thereof, an inward projection from said dome-shaped member at said cen-

tral portion, and a centrally-apertured disc of electro-conductive material received over the end of said inward projection in spaced relationship from said casing, said annular edge portion of said dome-shaped part having integral 5 angularly extending mounting flange means, said flange means being apertured for receiving screws, said end portion of said inward projection having an annular groove therein for retainingly receiving the apertured edge portion 10 of said disc.
